UNITED STATES PATENT OFFICE

PETER S. HARDY, OF STRATFORD, CONNECTICUT, AND THEODORE SMITH, OF CHICAGO,
ILLINOIS, ASSIGNEES TO UNITED HEALTH EQUIPMENT COMPANY, OF CHICAGO,
ILLINOIS, A CORPORATION OF ILLINOIS

DESIGN FOR AN EXERCISING APPARATUS

Application filed May 9, 1932. Serial No. 43,763. Term of patent 7 years.

To all whom it may concern:

Be it known that we, PETER S. HARDY and THEODORE SMITH, both citizens of the United States, residing at Stratford, county of Fairfield, State of Connecticut, and Chicago, county of Cook, State of Illinois, respectively, have invented a new, original, and ornamental Design for an Exercising Apparatus, of which the following is a specification, reference being had to the accompanying drawing forming a part thereof.

The figure is a perspective view of our exercising apparatus, showing our new design.
We claim—

The ornamental design for an exercising apparatus as shown.

In witness whereof we affix our signatures.

THEODORE SMITH.
PETER S. HARDY.
